UNITED STATES PATENT OFFICE.

WILLIAM V. ORR, OF CLEVELAND, OHIO.

VACUUM CLEANING DEVICE.

Original application filed April 19, 1912, Serial No. 691,966. Patent No. 1,210,522, dated January 2, 1917.
Divided and this application filed November 25, 1916. Serial No. 133,340.

To all whom it may concern:

Be it known that I, WILLIAM V. ORR, a citizen of the United States, residing at Cleveland, in the county of Cuyahoga and State of Ohio, have invented a certain new and useful Improvement in Vacuum Cleaning Devices, of which the following is a full, clear, and exact description, reference being had to the accompanying drawings.

10 This invention relates to vacuum cleaning devices, and has for its object the provision of an apparatus of this nature of simple and compact form and efficient operation; the provision of means in a device of this character whereby the air stream is directed along the surface of the floor covering, the better to dislodge litter lying thereon; the provision of an improved brushing apparatus whereby the dirt particles may be loosened from a textile surface and delivered into the air current without becoming entangled in the brush; the provision in a suction cleaner nozzle of a separate brush chamber connected with the suction passage only 20 in the lower part thereof; the provision of new and improved means for adjusting the operating parts with reference to the surface on which they are used; while further objects and advantages will become apparent 25 in the course of the following description and claims.

30 In the drawings accompanying and forming a part of this application, I have illustrated certain simple embodiments of my said invention, one of the same being copied from my prior application filed April 19, 1912, Serial No. 691,966, (now Patent #1,210,522, granted January 2, 1917) of which the present application is to that extent 35 a division; and the remaining embodiments being now illustrated for the first time; although it will be understood that other constructions than those specifically described and illustrated herein may be employed 40 within the scope of my inventive idea. In these drawings, Fig. 1 is a top plan view of a vacuum cleaner constructed in accordance with my invention, a portion of the casing being broken away to show the arrangement 45 of the air passages, and a part of the bag and handle being omitted; Fig. 2 represents a side elevation of a complete vacuum cleaner made in accordance with my invention; Fig. 2^a is a detail view showing the 50 caster adjustment; Fig. 3 is a side elevation

tional view of a portion of the brushing head illustrated in Figs. 1 and 2, a part of the gear casing being broken away so as to show the method of driving the brush; Fig. 4 is a vertical, transverse, cross-sectional view taken on the line 4-4 of Fig. 1 and looking in the direction of the arrows; Fig. 5 is a detail cross-sectional view taken on the line 5-5 of Fig. 3 and disclosing the manner of supporting and adjusting the gears; Fig. 6 is a perspective view of a modified form of cleaner embodying my improvements, a part of the casing being broken away; Fig. 7 is a side elevational view of the device shown in Fig. 6; Fig. 8 is a vertical, longitudinal, 70 sectional view through the device shown in Fig. 6; Fig. 9 is a top plan view of the cleaner shown in Fig. 6; Fig. 10 is a bottom plan view of the cleaner shown in Fig. 6; and Fig. 11 illustrates another modification.

Describing the parts by reference characters, attention being first paid to Figs. 1 to 5 inclusive, 1 represents the motor and 2 the fan casing of my improved vacuum cleaner, said motor being preferably supported with its shaft substantially horizontal and said fan casing being attached directly to the forward end of the motor so that a direct-connected fan may be employed. The periphery of this casing is formed with a substantially horizontal discharge pipe 3. Carried by the rear end of the fan casing are suitable brackets 5-5, to which are pivoted the arms 6 of the handle 7 whereby the device is operated, said handle also preferably serving as a conduit for the wires 8 whereby energy is conveyed to the motor. Secured to the outlet pipe 3 is the lower end of the porous dust bag 9, the upper end of which is suspended from the handle 7 in any convenient manner. The motor casing is provided at its rear part with a suitable supporting roller 16. The forward face of the fan casing is provided with a substantially central aperture for the admission of air to the fan and with spaced threaded apertures for the reception of thumb screws 20 by which the various nozzles or collecting attachments may be affixed thereto. 90

100

The brushing head which I have here shown comprises a pair of vertical boxes 25 and 26 having closed tops and open bottoms as shown in Fig. 5. The outer walls of these boxes are represented at 25^a and 26^a respectively, and their inner walls at 25^b and

26^b respectively. The rear edges of these walls are preferably substantially vertical as shown in Figs. 2, 3 and 4, but their forward edges are inclined at the angle which is 5 to be given to the forward side of the cleaner head. These walls are parallel to each other and to the motor axis at their rear portion but are bent outwardly at their forward ends so as to converge to a point at 27. The 10 boxes 25 and 26 are secured together by means of a casing plate 28 of sheet metal having an inverted V shape, the forward side of this plate being secured to the forward edges of the walls 25^a and 26^a. The 15 rear side of said plate is notched as at 29 so as to fit between the walls 25^b and 26^b. This construction provides an inverted trough-shaped casing having at each end a vertical, rearwardly-projecting ear, the outer face 20 of which is substantially flush with the end of the casing. The edges of the plate 28 are horizontal and are preferably rolled as at 31 both for the sake of stiffness and for the purpose of preventing their catching in the 25 carpet or other fabric upon which the device is used. These edges constitute the lips of the inlet mouth into which the carpet is raised by the suction.

The inner faces of the walls 25^b and 26^b 30 are also formed with flanges 33 spaced from the plate 28 but converging toward the same as they approach the lower edges of the walls, and to these flanges is rigidly secured, as by riveting, a second V-shaped metallic 35 plate 34 constituting a brush shield. As will be seen by reference to Fig. 4, the apices of these plates are spaced apart a considerable distance, while their free edges or lips approach very closely together so as to define 40 the narrow inlet slits 35 and 36 at the forward and rear sides of the casing respectively. By reference to Fig. 1 it will be seen that the length of the slit 35 is greater than that of the slit 36 from the fact that 45 the slit 35 extends between the outturned ends 27 of the boxes 25 and 26, whereas the mouth 36 is limited to the space between the inner walls of these boxes. Furthermore, the lips of the plate 34 are terminated 50 at a point slightly above the lips of the plate 28 as shown at 37, (Fig. 4) for a purpose that will be hereafter explained. The upper or apex portion of the plate 28 is formed with an aperture 40 around which is secured 55 the flange 41 of an elbow 42, the horizontal arm of which is formed with a plate 43 adapted to be secured to the forward face of the fan-casing 2 by means of the thumb screws 20, above mentioned.

In order to prevent the formation of dead 60 air spaces at the ends of the chamber defined by the plates 28 and 34, I have shown between these plates at each side of the aperture 40 an angular deflecting web or partition 45, the ends of which lie closely adja-

cent to the ends of the slits 35 and 36, and the middle or apex portions of which lie closely adjacent to the sides of the aperture 40. Also in order to effect the uniform distribution of suction throughout the entire 70 length of the slits, I have shown deflecting members 46—46 located in the passageways. However, the present invention is wholly independent of these devices, which may or 75 may not be used.

Formed in the walls of the boxes 25 and 26 is a horizontal row of aligned vertical slots 50 (only one being shown, in the inner wall 26^b, Fig. 3) through which is projected a shaft 51 having at its ends the floor-wheels 52, preferably rubber tired in the usual manner. Formed in the inner walls 25^b and 26^b of the boxes at points vertically above the slots 50 are other vertical slots 53 each of which receives the shank of a thumb screw 54 to the inner end of which is secured the upper end of a vertical link 55 the lower end of which surrounds and forms a bearing for the shaft 51. The surface of the plate adjacent to the slot 53 is preferably ribbed or corrugated as at 56 and the thumb screw provided with a similarly corrugated washer 57 whereby the link can be firmly secured in position and the brushing head secured at a fixed distance above the floor as will be obvious. Formed in the walls 25^b and 26^b upon arcs having centers coinciding substantially with the centers of the slots 50 are other slots 60 through which extends the horizontal shaft 61. The portion of this shaft between the plates 25^b and 26^b carries the cylindrical brush 62, while the portions thereof included within the limits of the boxes 25 and 26 are journaled in links 63, the other ends whereof surround the shaft 105 51. Inside one of these boxes as 26, the shaft 61 is provided with a pinion 64 which meshes with the gear wheel 65 carried by the shaft 51. In Fig. 5 I have illustrated two links 63 one at each side of the pinion 110 64, although it is probable that one of these links will frequently be omitted. The upper portion of each of the walls 25^a and 26^a is formed with a vertical slot 66 above the adjacent end of the shaft 61 and through 115 this slot is projected a thumb screw 67, the inner end of which engages a vertical link 68, the lower end whereof is apertured for the reception of the shaft 61, and forms a bearing therefor. This slot is preferably 120 covered by a corrugated washer 69 similar to the washer 57 above mentioned and serving to permit the adjustment of the height of the brush 62.

The links 55, 63 and 68 constitute a frame 125 to which the carrying wheels and brushing mechanism are journaled, and by adjusting the same the relation of the head and brush to the working surface and to each other can be varied without disturbing the driving re- 130

lation between the brush and wheels. The frame is secured in such adjusted position by the screws 53 working in the slots 54 and by the links 68, bolts 67, and slots 69. The 5 inter-connection of the shafts 51 and 61 keeps the same always parallel and at a fixed distance apart insuring the easy and noiseless running of the gears, while the enclosure of the gearing prevents the same from 10 catching upon furniture, clothes, or fingers, or from becoming clogged with the dirt passing through the device. This method of gearing also effects the rotation of the brush 62 in the direction opposite to the motion of 15 the wheels of the device and thus throws the dirt particles forward. The air rushing through the slits 35 and 36 picks up these particles and carries them to the bag 9, while if any particles are not caught up by the air 20 the first time they are lifted by the brush, they are promptly recovered by the brush a second time and delivered to the air stream. The location of the inner lips above the outer lips affords constant communication between 25 the slits and brush chamber, so that dirt particles agitated by the brush may be thrown directly into the path of the air stream. Also the rush of air horizontally over the carpet is very effective while sealing contact of the lips with the carpet is prevented. 30 The function of the casing 34 is two-fold, in that it prevents the dirt and dust from being drawn directly into and through the brush thus avoiding the clogging and fouling of 35 the brush, and that it also increases the effectiveness of the device by concentrating the suction upon the two narrow slits 35 and 36 instead of distributing the same over a large area. 40 I have shown the caster 16 as adjustably attached to the motor casing, as by having its shank 17 slidably mounted in the supporting bracket 15 and releasably secured by the pin 18 carried by the spring 19 and engaging any one of several apertures in that shank, and in adjusting the device shown in Figs. 1 to 5, it is preferable to adjust the wheels 52 and the caster 16 simultaneously, so that the bottom of the casing or head may 50 always remain parallel with the floor.

In Figs. 6 to 10 inclusive, I have shown a modified construction of cleaner in which a different form of brush chamber is employed together with modified means for driving 55 said brush. In these views, 1^a represents the motor casing, 2^a, the fan casing, 7^a, the handle, and 9^a, the dust bag. This fan chamber is supported in substantially horizontal position with its axis arranged in a 60 fore and aft position, and projecting from the forward wall of this fan chamber is a laterally-flaring, downwardly-inclined, collecting nozzle, having an upper wall 70 and a lower wall 71, including between them the 65 axial inlet opening 72 of the fan chamber.

The wall 71 is preferably made with a uniform uninterrupted slope down to its lowermost edge, where it terminates in a horizontal lip 73. The wall 70 extends forward at a smaller slope than the wall 71, and terminates in a depending lip 74 at a considerable distance in front of the lip 73, the plane of the lip 74 being slightly the higher. At their outer lateral edges, the plates 70 and 71 are connected by vertical walls 75—75 arranged in a forwardly flaring relation, the lower edges of these walls being substantially horizontal and level with the lip 73 excepting at their forward edges where they are sloped upwardly to meet the lip 74 as shown at 76. The result of this construction is to provide 80 a narrow horizontal intake slot or crevice 77 across the front of the machine, the remainder of the nozzle being closed against 85 the lateral inrush of air.

Supported inside this nozzle, immediately above the plane of the inlet mouth, is a filler of sheet metal or other suitable substance, the same being secured in any suitable manner, rivets 78 being here illustrated. This filler preferably comprises a tapering portion 80 secured inside the neck portion of the nozzle and depending in a long sweep forming a throat portion which terminates in a kind of curtain 81, whose lower edge extends from one side of the nozzle to the other and is spaced above (and in the present embodiment slightly forwardly of) the lip 73 to define an inlet slot of considerable suction. Immediately in front of this curtain 90 there is provided a substantially semi-cylindrical chamber 82 extending from one side of the nozzle to the other for the reception of a brush; and in front of this chamber the plate extends forwardly in a substantially horizontal manner to the lip 74 in the form of a kind of bridge 83 to the lower face of which are attached the teeth 84.

Each of these teeth consists of a diagonally disposed plate or rib of considerable length carried by the bridge 83 and extending downwardly beyond the lip 74, and preferably substantially to the plane of the lip 73. The teeth on opposite sides of the center line are inclined in opposite directions as shown in Fig. 10, each being generally parallel to the side wall of the nozzle to which it is nearest; and the width of the teeth is preferably rather small, but their length and inclination is such that each overlaps the other to some extent as shown in Fig. 10, excepting the middle teeth which may be conveniently spaced apart for the passage of heavier objects which are customarily taken up through the center of the machine. The result of this construction is that air rushing through the crevice 77 and across the top of the carpet tends to blow refuse lying thereon towards the lip 73, whence it is easily swept up the incline wall 110 115 120 125

71, and into the suction chamber. At the same time, the diagonal arrangement of the teeth 84 serves to press the nap of the carpet first one way and then the other, with a kind 5 of swaying motion which loosens and disengages dust particles which would otherwise not be removed; and the lateral rubbing movement combined with the movement of the air tends to roll lint and thread into 10 little balls which can be picked up by the air stream.

The construction heretofore described will produce a very efficient and satisfactory cleaner even without the employment of 15 brushing devices of any kind, and such brushing devices, when employed, may be of any suitable or desired nature. The type shown herein consists of a rotatable body 20 journaled substantially concentrically with the chamber 82, the filler serving as a shield for the brush similarly to the shield 34 in Figs. 1 to 5, and the rotatable body having one end connected to a shaft 86 suitably journaled in the end wall of the chamber. The outer end of this shaft traverses 25 a hollow casing 87, and is provided between the walls of this casing with a pinion 88. This casing is of a flat elongated nature with 30 parallel side walls between which are journaled an idler gear 89 meshing with the pinion 88, and a driving gear 90 meshing with the idler gear. The hub of the driving gear projects through the inner wall of the gear casing and is formed with clutch teeth 35 shown at 91 in Fig. 10.

Journaled to the bottom of the nozzle is a rock shaft 92, having crank shaped ends 93 upon whose extremities are journaled the floor rollers 94—94. Suitable means are provided for rocking this shaft to raise and 40 lower the nozzle with respect to these rollers, the means here shown comprising a set screw 95 resting upon the cranked portion of the shaft for moving the same in one direction 45 and a coil spring 96 wound around the shaft for moving the same in the opposite direction. The face of one of the wheels 94 is formed with clutch teeth complementary to the teeth 91, and arranged to cooperate 50 therewith in driving the said brush, there being sufficient looseness between these clutch members to permit the necessary adjustment in the height of the nozzle, which is not very great.

55 In the preceding embodiments, I have illustrated the brush chamber as formed by a separate sheet metal filler inset within the nozzle, but I do not confine myself to such a construction, since all of the advantages of 60 my invention can equally well be secured by forming the brush chamber integral with the nozzle itself. Thus in Fig. 11, the upper wall 100 of the nozzle is formed at its lower part with a pair of spaced depending parallel flanges 101, 102, defining between them

a brush receiving chamber 103. The lower edge of the flange 101 extends to a point lower than the edge of the flange 102 and forms one lip of the inlet mouth, the other lip 104 being carried by the extremity of the 70 bottom wall 105 of the nozzle. This lip 104 is preferably located slightly lower than the lip 101, and is spaced from the flange 102 sufficiently to form a narrow inlet slot which 75 extends from one end of the nozzle to the other. Within the chamber 103 is mounted a brush 106, here shown as of the stationary type.

In all of these constructions, the formation of the brush chamber separate from the 80 main passageway prevents the lint and dust from being drawn into and entangled with the brush; the termination of the chamber wall at a point near, but spaced above the working surface inside of the nozzle, causes 85 a flow of air along the top of the working surface which exhibits a peculiar efficiency in removing dust and litter; the concentration of the air stream in this narrow slot causes it to be distributed with appreciable 90 uniformity throughout the entire length of the nozzle, and so increases the velocity as greatly to enhance the lifting power of the air stream; and sealing contact of the nozzle with the floor fabric is always prevented; however, it will be obvious that these results could still be secured even though the arrangement and construction of the device were changed materially from anything shown herein, wherefore I do not restrict myself to the details here exhibited, except as the same may be specifically recited in the claims hereto annexed, or rendered necessary by the prior state of the art.

Having thus described my invention, what I claim is—

1. In a vacuum cleaning apparatus for floors and the like, in combination, a head having a downwardly opening mouth, a rotatable brush supported within said mouth, means for revolving said brush, and a shield interposed between said brush and one of the walls of said mouth to form a narrow intake opening, the lower edge of said shield terminating at a higher level than the lips of said mouth.

2. In a vacuum cleaning apparatus for floors and the like, in combination, a head having a downwardly opening mouth, floor engaging wheels carried by said head and journaled upon an axis transverse to the direction of movement thereof, a cylindrical brush supported within said mouth upon an axis substantially parallel to that of said wheels, gearing between said wheels and brush and a shield surrounding said brush and spaced from the walls of said mouth to form a narrow intake opening at the side of said brush and substantially parallel thereto, said shield depending below the

center of said brush but terminating above said mouth.

3. In a vacuum cleaning apparatus, in combination, a head having a downwardly opening horizontal mouth, a rotatable brush journaled in said mouth, a pair of supporting wheels pivoted to said head, driving connections between said wheels and said brush, means for adjusting said wheels and said brush separately towards and from the plane of said mouth, and a suction connection opening into said mouth within and slightly above the plane thereof.

4. In a vacuum cleaning apparatus, in combination, a head having a downwardly opening horizontal mouth, a rotatable brush journaled in said mouth, a pair of supporting wheels pivoted to said head, gearing connecting said wheels to said brush, means for adjusting said wheels and said brush independently towards and from said mouth, and links pivoted to said wheels and brush for preventing a change in the distance between the same.

5. In a vacuum cleaning apparatus, a nozzle having a downwardly opening inlet mouth, a frame adjustably secured to said nozzle carrying wheels journaled to said frame, agitating devices located in said nozzle and operatively connected to a rotating part of said apparatus, means for raising and lowering said frame relatively to said nozzle so as to support said nozzle at different heights above the working surface, and suction producing means operatively connected to said nozzle.

6. In a vacuum cleaning apparatus, a casing having a collecting nozzle formed with a downwardly facing inlet mouth, a rotatable brush journaled in said casing, a supporting device adjustably secured to said casing, carrying wheels journaled to said supporting device one at each side of the mid-point of said nozzle and operatively connected to said brushing means, means for holding said supporting device in varying adjusted positions whereby said nozzle may be supported at different heights above the floor, and suction producing means operatively connected to said nozzle.

7. In a vacuum cleaning apparatus, a supporting frame carrying wheels journaled to said frame, a casing mounted on said frame and having a collecting nozzle formed with a downwardly facing inlet mouth, means for holding said casing in varying adjusted positions with reference to said frame, whereby said inlet mouth may be supported at different heights above the floor, brushing devices carried by said casing and operatively connected to said carrying wheels, and suction producing means operatively connected to said nozzle.

8. In a vacuum cleaning apparatus, a casing having an elongated nozzle formed with

a downwardly facing inlet mouth, a movable frame carried by said casing, brushing mechanism carried by said casing, carrying wheels journaled to said frame, one adjacent to each end of said nozzle and operatively connected to said brushing mechanism, and means for holding said frame in any position to which it may be moved whereby said nozzle will be supported at different heights above the working surface, said brushing mechanism also being connected to said frame so that its position relatively to said inlet mouth will vary with the adjustment of said frame.

9. In a vacuum cleaning apparatus, in combination, a head having a horizontal downwardly opening mouth adjacent to the floor, floor engaging wheels carried by said head and journaled upon an axis transverse to the direction of movement thereof, a brushing device supported within said mouth, connections between said wheels and said device whereby said device will be actuated by the movement of said wheels, and a shield embracing said brushing device and spaced from the lips of the mouth so as to form a narrow slot at each side of said brushing device transverse to the direction of movement of said head.

10. In a vacuum cleaning apparatus, in combination, a metallic casing having an inverted V-shape in cross section, a cylindrical brush journaled in said casing upon a substantially horizontal axis, floor wheels carried by said casing, driving connections between said floor wheels and brush, a second V-shaped casing within said first casing and embracing said brush, said second casing having its edges spaced from the forward and rearward edges of said first casing to define a pair of narrow elongated slits, the sides of said casings being substantially straight and diverging from each other as they recede from said slits.

11. In a vacuum cleaning apparatus, the combination, with a pair of spaced upright boxes and a metallic plate connecting said boxes and forming an elongated head, the adjacent sides of said boxes being formed with arcuate slots, of a cylindrical brush in said head and having a shaft extending through said slots, a second shaft journaled in said boxes at substantially the center of the circle defined by said slot, links in said boxes embracing both of said shafts intermeshing gears carried by said shafts, floor engaging wheels carried by the latter shaft, and means for adjusting said shafts separately towards and from the floor.

12. In a vacuum cleaning apparatus, the combination, with a pair of spaced upright boxes and an inverted V-shaped plate connecting said boxes and forming a head, the adjacent sides of said boxes being formed with attaching flanges within the limits of

said first plate, of a second V-shaped plate secured to said flanges and having its edges spaced from the edges of the first plate to form slits, agitating means beneath said second plate, a shaft extending through the inner wall of one of said boxes and connected to said agitating means, a second shaft journaled in each of said boxes parallel to said first shaft, intermeshing gears carried by 10 said shafts, and floor engaging wheels carried by the latter shaft.

13. In a vacuum cleaning apparatus, the combination, with an electric motor and a fan casing secured to one end of said motor, 15 said fan casing having an aperture in the side opposite said motor, of a supporting wheel carried by said motor, a head having a flanged discharge pipe detachably connected to the forward face of said fan casing, and wheels carried by said head and co-operating with said first wheel to support said motor with its shaft substantially horizontal.

14. In a vacuum cleaning apparatus, the combination, with an electric motor and a fan casing secured to one end of said motor, said fan casing having an aperture in the side opposite said motor, of a supporting wheel carried by said motor, a suction nozzle carried by the forward face of said fan casing, and floor-engaging supporting means carried by said nozzle and co-operating with said wheel to support said motor with its shaft substantially horizontal.

15. In a vacuum cleaning apparatus, a suction head having a pair of spaced parallel narrow suction mouths, the distance between said mouths being of greater width than either of said mouths, and a pair of 20 floor-engaging carrying wheels journaled to said head, one at each side thereof, upon axes parallel to said mouths and between the vertical planes which include said mouths.

16. In a vacuum cleaning apparatus, the combination of a casing having downwardly extending rear and forward walls, a rotatable brush supported within said walls, means for revolving said brush a shield interposed between said brush and one of the walls to form a narrow intake opening, the lower edge of said shield terminating at a higher level than the edges of said walls, and a suction device connecting with said intake opening.

17. In a vacuum cleaning apparatus, the combination of a casing having downwardly extending rear and forward walls, floor engaging wheels carried by said casing and journaled upon an axis transverse to the direction of movement thereof, a cylindrical brush supported within said walls upon an axis substantially parallel to that of said wheels, means for driving said brush and 25 a shield surrounding said brush and spaced

from the walls to form a narrow intake opening at the side of said brush and substantially parallel thereto, said shield depending below the center of said brush but terminating above the edges of said walls, and a suction device communicating with said opening.

18. In a vacuum cleaning apparatus, the combination of a casing having downwardly extending rear and forward walls, a rotatable brush journaled within said walls, a pair of supporting wheels, pivoted to said casing, gearing connecting said wheels to said brush, means for adjusting said wheels and said shaft independently toward and from 75 the lower edges of said walls, and means for preventing a change in the distance between said wheels and said brush.

19. In a vacuum cleaning apparatus, the combination of a casing having downwardly 80 extending and diverging rear and forward walls, a frame adjustably secured to said casing and carrying wheels journaled thereto, agitating devices located within said divergent walls and operatively connected 90 to said carrying wheels, means for raising and lowering said frame relatively to said casing so as to support said casing at different heights above the working surface, and suction producing means operatively connected to the inside of said casing.

20. In a vacuum cleaning apparatus, the combination of a casing having downwardly 100 extending and diverging rear and forward walls, floor engaging wheels carried by said casing and journaled upon an axis transverse to the direction of movement thereof, a brushing device supported within said walls, connections between said wheels and said device whereby said device will be actuated 105 by the movement of said wheels, and a shield embracing said brushing device and spaced from the lower edges of said walls so as to form a narrow slot at each side of said brushing device transverse to the direction of movement of said casing.

21. In a suction cleaner, a casing, an elongated nozzle carried thereby and transversely arranged relatively thereto, a frame adjustably secured to said nozzle, carrying 115 wheels journaled to said frame, agitating devices located in said nozzle and operatively connected to said carrying wheels, and means for raising and lowering said frame relatively to said nozzle so as to support 120 said nozzle at different heights above the working surface.

22. In a suction cleaner, a collecting nozzle and a movable frame therein, an agitating device carried by said frame, means for raising and lowering said frame relatively to said nozzle so as to support said agitating device at different heights above the working surface, and carrying wheels for said nozzle.

23. In a suction cleaner, a casing, an elongated nozzle carried thereby and transversely arranged relatively thereto, frame members movably secured to said nozzle, an agitating device carried by said frame members, means for raising and lowering said frame members relatively to said nozzle so as to support said agitating device at different heights above the working surface, carrying wheels for said nozzle, and means for operating said agitating device in all positions of its adjustment.

5 wardly facing inlet mouth, a supporting device movably secured to said casing, a rotatable brush journaled in said supporting device and movable therewith to a position either inside of or outside of said mouth, means for securing the said supporting device in varying adjusted positions whereby said brush is adjusted relatively to said inlet mouth, carrying wheels for said casing and means for driving the brush.

10 15

24. In a suction cleaner, a casing having a collecting nozzle formed with a down-

20

In testimony whereof, I hereunto affix my signature.

WILLIAM V. ORR.
